UNITED STATES PATENT OFFICE

103,445

DESIGN FOR AN AUTOMOBILE RADIATOR ORNAMENT

Winfield Scott Scroggs, Waka, Tex.

Application December 19, 1936, Serial No. 66,656

Term of patent 3½ years

To all whom it may concern:

Be it known that I, Winfield Scott Scroggs, a citizen of the United States, residing at Waka, in the county of Ochiltree and State of Texas, have invented a new, original, and ornamental Design for an Automobile Radiator Ornament, of which the following is a specification, reference being had to the accompanying drawing, forming part thereof.

Figure 1 is an elevational view of one side of an automobile radiator ornament, showing my new design.

The side of the automobile radiator ornament opposite that shown in Figure 1 is substantially the same as that shown in Figure 1.

I claim:—

The ornamental design for an automobile radiator ornament as shown and described.

WINFIELD SCOTT SCROGGS.
